CLAIM

The ornamental design for a handle for forks, spoons and toothbrushes, as shown and described.

DESCRIPTION

FIG. 1 is a perspective view of a handle for forks, spoons and toothbrushes showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines showing fork tines in FIGS. 1-5 and 7 are environmental only and form no part of the claimed design.
